UNITED STATES PATENT OFFICE.

WILLIAM E. KIER, OF CHICAGO, ILLINOIS, ASSIGNOR TO INDIVIDUALIZING COMPANY OF ILLINOIS, OF CHICAGO, ILLINOIS, A CORPORATION OF ILLINOIS.

TYPE-CASTING MOLD.

Application filed July 25, 1924. Serial No. 728,058.

This invention relates to a slug casting mold for a linotype machine or any slug casting machine in which type slugs are cast and typed for use in printing presses.

5 In a printing press for printing form letters, such slugs are used for printing the name and address of the person at the same time that the body of the letter is being printed. In a certain type of such machine, the slugs 10 are placed in a galley and fed by gravity into the jaw of a feeding element that advances the slug into the plane of the printing bed plate or chase and that also retracts the same. This jaw of the feeding element takes over 15 the outer margin of the slugs, thereby shortening the space which can be typed. Further as the slugs as now constructed descend in the galley, they frequently become jammed or out of proper alignment causing waste in 20 the printed matter and consequent loss of time.

It is an object of this invention to overcome these defects in the provision of a mold in which slugs can be cast with lateral slots or 25 notches that are adapted for cooperating with guide ribs in the galley for maintaining the slugs in proper alignment, and that are also adapted for receiving the jaw members of the feeding element of the printing press so that the printing may extend the full 30 length of the slug.

The invention consists of the novel structure and combinations hereinafter described and more particularly pointed out and defined in the appended claims.

35 In the accompanying drawings which illustrate a preferred embodiment of this invention and in which similar reference numerals refer to similar features in the different views:

Figure 1 is a fragmentary elevational view of the mold gear of a linotype machine.

Figure 2 is a sectional view taken upon the line 2-2 of Figure 1.

40 Figure 3 is a sectional view upon the line 3-3 of Figure 1.

Figure 4 is a sectional view upon the line 4-4 of Figure 1.

Figure 5 is a reduced top plan view of the 45 mold gear.

Figure 6 is a top plan view of a cast slug.

As shown on the drawings:

Referring to the drawings the numeral 1 represents the usual mold gear of a linotype

55 machine. This gear is provided with a mold 2 in which a slug 14 is cast and typed. The gear is mounted upon a stationary support 3 and is intermittently rotated by a pinion 1^a. When the mold 2 is in its upper horizontal position, the slug is cast and typed. The gear 60 then makes a three-quarter turn when it comes to a dwell for the ejection of the slug.

This invention concerns itself with mechanism whereby slots 15 may be cast in the lateral edges of the slug and which operates automatically during the operation of the machine. The form of mechanism illustrated for carrying out this invention comprises a pair of rectangular reciprocating slot forming elements in the form of rods 4 which are 65 suitably supported and guided upon the gear wheel 1 for entering the ends of the mold 2 as shown in Figures 1 and 2. The outer end of each element 4 is pivotally connected to the upper slotted end of one arm 5 of a bell 70 crank lever to allow for arcuate movement of the lever. The other arm of each bell crank lever is provided at its end with a roller 7 that lies upon the periphery of a stationary 75 cam 8 secured upon the end of the support 3. Each bell crank lever is provided with an extension 9 having a terminal aperture for receiving the end of a rod 10 which is pivoted at its other end to the gear wheel 1. A coil 80 spring 11 surrounds each rod 10 and is confined between the extension 9 and an abutment on the pivoted end of the rod 10. In referring to Figure 1, it will be noted that the cam 8 has a concentric portion 12 which 85 extends about three-quarters of the circumference of the cam, the upper portion or quarter of said cam being in the form of a dwell 13. When the rollers 7 are positioned in the dwell, the rods 4 are a short distance in the mold 2, in this position of the parts which is illustrated in Figure 1, the slug is cast and typed 90 in the mold. After the slug is cast, the gear 1 will rotate about three-quarters of a revolution for the ejection of the cast slug. During this rotation of the gear 1, the rollers 7 will be brought upon the concentric portion 95 of the cam 8 whereby the bell crank levers are automatically operated for withdrawing the slot forming elements 4 whereby the slugs are released so that the same may be ejected. After the slug is ejected, the gear 1 will rotate 100 about a quarter turn in the same direction. This will bring the mold 2 into its upper

90

95

100

105

horizontal position as shown in Figure 1, with the rollers 7 in the dwell or depression 13, allowing the springs 11 to operate the bell crank levers for injecting the ends of the slot forming elements 4 into the mold 2 in position for casting another slug.

From the foregoing, it will be apparent that during the rotation of the mold gear 1, the slot forming elements are automatically injected into and withdrawn from the mold in timed relation with the other parts of the machine so that the slugs may be formed with slots and ejected from the mold.

I am aware that many changes may be made, and numerous details of construction may be varied through a wide range without departing from the principles of this invention, and I therefore do not purpose limiting the patent granted hereon, otherwise than necessitated by the prior art.

I claim as my invention:

1. In a slug casting machine, a rotary member formed with a mold for casting slugs, slot forming elements slidable into and out of the ends of said mold, bell crank levers pivoted upon said member, one arm of each lever being connected to a slot forming element, a stationary cam whereby said elements are withdrawn from said mold, and yielding means for injecting said elements into said mold.
2. In a slug casting machine, a rotary member having a slug forming mold, slideable slot forming elements carried by said member, a stationary cam and lever mechanism connected to said elements and operable through contact with said cam for withdrawing said elements from the ends of said mold.
3. In a slug casting machine, a rotary member having a mold, slot forming elements adapted for entering the ends of said mold to cast slots in the slug and means operable during the rotation of said member of controlling said elements.
4. In a slug forming mold, a pair of slot forming elements adapted for entering the ends of the mold for forming slots in the slugs, and means for automatically with-

drawing said elements in order that the slugs may be ejected.

5. In a slug casting machine, the combination with the slug forming mold, of slot forming elements for entering the ends of said mold and mechanism automatically operated during the operation of said machine for controlling said slot forming elements with respect to said mold.

6. In a slug casting machine, the combination with the slug forming mold, of slot forming elements reciprocable with respect to said mold, and mechanism automatically operated during the operation of said machine for causing said elements to reciprocate into and out of the ends of said mold.

7. In a slug casting machine, the combination with the rotary slug forming mold, of reciprocating slot forming elements carried thereby, yielding means for causing said elements to enter said mold to form slots in the opposite ends of a slug, and means automatically operated during the rotation of said mold for retracting said elements.

8. In a machine for casting type slugs, the combination of a mold arranged for casting type slugs, slides mounted in said mold and arranged to be projected thiereinto to form slots in the ends of the slug, and automatic means for periodically withdrawing said slides to permit the slug to be ejected from the mold.

9. In a machine for casting type slugs, the combination of a mold arranged for casting type slugs, slides mounted in said mold and arranged to be projected thiereinto to form slots in the slug, and means for periodically withdrawing said slides to permit the slug to be ejected from the mold, said means including a cam, bell crank levers attached to said slides and arranged for actuation by said cam, and yieldable means arranged to urge the slides into the mold and the bell crank levers against the cam.

In testimony whereof I have hereunto subscribed my name.

WILLIAM E. KIER.
